UNITED STATES PATENT OFFICE.

FRED FLEISCHAUER, OF NEW MILFORD, NEW JERSEY, ASSIGNOR TO NEW YORK LIGHTING FIXTURE MANUFACTURING CO., OF NEW YORK, N. Y., A CORPORATION OF NEW YORK.

DESIGN FOR A CHANDELIER FOR LIGHTING FIXTURES.

Application filed July 20, 1922. Serial No. 3,145. Term of patent 7 years.

To all whom it may concern:

Be it known that I, FRED FLEISCHAUER, a citizen of the United States, and residing at New Milford, in the county of Bergen and State of New Jersey, have invented a new, original, and ornamental Design for a Chandelier for Lighting Fixtures, of which the following is a specification, reference being had to the accompanying drawing, forming part thereof.

Fig. 1 is a plan view of a chandelier for lighting fixtures, showing my new design;

Fig. 2 is a side elevation of the same.

I claim—

The ornamental design for a chandelier for lighting fixtures, as shown.

FRED FLEISCHAUER.
